UNITED STATES PATENT OFFICE.

MAX C. BRUHN AND GEORGE F. MCGILL, OF CHICAGO, ILLINOIS.

SELECTIVE CHANGE-MAKER.

1,385,359.

Specification of Letters Patent. Patented July 26, 1921.

Application filed July 18, 1918. Serial No. 245,532.

To all whom it may concern:

Be it known that we, MAX C. BRUHN and GEORGE F. MCGILL, citizens of the United States, and residents of the city of Chicago, 5 in the county of Cook and State of Illinois, have invented certain new and useful Improvements in Selective Change-Makers; and we do hereby declare that the following is a full, clear, and exact description of 10 the same, reference being had to the accompanying drawings, and to the numerals of reference marked thereon, which form a part of this specification.

This invention relates to an improved 15 type of a change maker wherein a plurality of coin tubes for holding coins of different denominations are each provided with selective ejecting mechanisms so arranged to permit one or more coins to be 20 ejected from each of the tubes independently of or simultaneously with the operation of any selective number of said coin tube ejecting mechanisms.

It is an object of this invention to provide 25 a change maker wherein any selected number of coin ejecting mechanisms may be operated simultaneously by one hand of an operator to make change comprising a selective number of coins of different denominations.

It is also an object of the invention to construct a change maker having the coin ejecting keys arranged to permit the same to be selectively operated by one hand of 35 an operator to produce change comprising a selective combination of coins of the same or different denominations.

A further object of the invention is the construction of a change maker wherein coin 40 tubes for coins of different denomination are each equipped to permit a selective ejection of coins therefrom.

Another object of this invention is to provide 45 a change maker wherein the keys of the ejecting mechanisms controlling the coins in the coin chutes for coins of different denominations are arranged to permit any change combination to be effected by a single operation produced by one hand of 50 an operator.

It is furthermore an object of the invention to construct a change maker wherein each coin container is equipped with a plurality of key operated ejectors adapted to be 55 selectively operated to effect the ejection of one or more coins from said container.

It is an important object of this invention to provide a selective change maker of simple and effective construction wherein a plurality of superimposed spring controlled 60 ejectors are provided for each coin tube to permit any desired combination of change to be made by simultaneously depressing a selective combination of keys of the various coin chutes.

Other and further important objects of this invention will be apparent from the disclosures in the specification and drawings.

The invention (in a preferred form) is illustrated in the drawings and hereinafter 70 more fully described.

On the drawings:

Figure 1 is a front elevation of a selective change maker embodying the principles of this invention.

Fig. 2 is a side elevation thereof.

Fig. 3 is a section taken on line 3—3, of Fig. 1, with parts shown in elevation.

Fig. 4 is a front elevation of the coin holder in vertical position.

Fig. 5 is a rear elevation thereof.

Fig. 6 is an enlarged top plan view of the coin holder positioned as shown in Fig. 4.

Fig. 7 is a bottom plan view thereof.

Fig. 8 is an enlarged sectional view taken 85 on line 8—8, of Fig. 6.

Fig. 9 is a fragmentary rear view of the upper corner thereof.

Fig. 10 is a fragmentary detail section on line 10—10, of Fig. 8, with parts in elevation.

Fig. 11 is a fragmentary detail section taken on line 11—11, of Fig. 8.

Fig. 12 is a fragmentary detail section taken on line 12—12, of Fig. 6, with parts 95 broken away and with parts in elevation.

Fig. 13 is a detail view taken on line 13—13, of Fig. 8.

As shown on the drawings:

The reference numeral 1, indicates a box 100 or casing having an opening 2, formed in the lower rear portion of one of the end walls thereof. The casing 1, is supported on legs 3, and has rigidly mounted on the inner surface of the front wall an inclined 105 trough, hopper or chute 4, which slants downwardly and rearwardly to permit the lower or discharge end 5, thereof to project through the opening 2, and curve rearwardly with the open end thereof disposed 110 above a coin receiver or cup 6, supported to the rear and toward one side of the cas-

ing. As clearly shown in Figs. 2 and 3, the rear wall of the casing 1, is higher than the front wall. The side walls of the casing are each cut or formed with a long inclined 5 edge 7, the lower end of which joins the lower end of a short inclined edge 8, which is disposed at right angles to the longer edge 7, to afford suitable seats to receive a coin holder and ejecting mechanism seated there- 10 in in inclined position.

The coin holder comprises a rack bent or formed to provide a plurality of parallel semi-cylindrical coin holding chutes, tubes or feed troughs numbered 9, 10, 11, 12 and 15 13, open at both ends and of different sizes to hold coins of different denominations. The tube 9, is adapted to receive pennies stacked therein, while the tube 10, is for nickels. Tube 11, is smaller and is designed 20 to hold dimes, while tubes 12 and 13, are for quarters and half dollars respectively. The coin holder is rigidly held seated in an inclined position to close the top of the casing 1, with the upper rear end of the holder 25 resting upon the upper edge of the rear wall of the casing. Integrally formed on the back of the coin holder are apertured lugs or arms 14, which are secured to the inner surfaces of the side walls of the casing 1, by 30 means of screws 15, or other suitable means. A metal plate, strap or base plate 16, projects across the bottom of the coin holder, and has the ends thereof bent upwardly at right angles to form flanges 17, which are 35 rigidly secured to the lower end portions of the sides of the coin holder. The base plate 16, rests against the upper edge of the front wall and projects into the casing, and has the inner margin thereof cut away to afford 40 semi-circular discharge openings 18, of different sizes corresponding to the sizes of the respective coin tubes. The discharge openings 18, extend to about half the depth of the coin tubes to permit the lowermost coin in 45 each tube to seat on the solid portion of said base plate.

Each coin tube is provided with a selective ejecting mechanism adapted to permit the ejection of one or more coins of the same de- 50 nomination from each of said tubes as desired. The ejecting mechanisms for the various tubes are practically the same with the exception that the tubes 9 and 10, are equipped with four ejectors, while the tubes 55 11, 12 and 13 are arranged with two ejectors. The number of ejectors for each tube, how- 60 ever, may be increased or decreased as desired. Due to the similarity in construction of the ejecting mechanisms, that for tube 9, 65 will be described and the respective reference numerals will be applied to corresponding parts for the ejecting mechanisms of the other tubes. The ejecting mechanism com- 70 prises ejector plates 19, 20, 21 and 22, dis- 75 posed one above the other in the order named

and all projecting through an opening 23, provided for the purpose in the lower portion of the tube 9, directly above the base plate 16. Each of the ejector plates for tubes 9 and 10, only has a portion thereof at 70 one of the front corners cut away as de- 75 noted by the reference numeral 24, to afford a clearance for the proper operation of the ejectors as hereinafter more clearly de- 80 scribed.

Each ejector plate has the longitudinal margins thereof bent upwardly at right angles to provide guide flanges 25, which extend from the front end of the ejector plate to within a short distance of the rear end 85 thereof, and acts to support the ejector plate disposed thereabove. The ejector plates are each provided with a longitudinal slot 26, in the front portion thereof. Said slots register with one another and projecting down- 90 wardly therethrough is a guide pin 27, the lower end of which is rigidly secured to the base plate 16, by means of a rivet or screw 28. A coin opening or pocket 29, is provided in each of the ejector plates of a diameter 95 sufficient to permit the respective coins to seat therein with the lowermost coin in the tube 9, resting upon the base plate 16. Mounted or secured upon the front project- 100 ing end of the ejector plates 19, 20, 21 and 22, are keys or buttons 30, 31, 32 and 33, re- 105 spectively, numbered or labeled 1, 2, 3 and 4, to correspond to the number of coins said buttons are adapted to eject when operated. Integrally formed centrally on the inner or 110 rear end of each of the ejector plates is a pair of parallel arms, forks or prongs 34, separated from each other by a guide slot 35, open at the rear end.

Rigidly secured across the upper portion 105 of the back of the coin holder by means of screws 36, is a mounting plate 37, to which is rigidly secured a plurality of yoked 110 brackets having apertured lugs or arms 38, one bracket being disposed at the back of 115 each of the coin tubes. Supported by said lugs 38, is a rod or shaft 39, upon which is rotatably mounted a plurality of levers 40, one for each of the coin tubes. Each of the levers 40, has the upper end thereof 120 yoked or U-shaped, as denoted by the ref- 125 erence numeral 41, to permit the same to be engaged on the shaft 39, between a pair of the lugs 38, to hold the lever in proper position. The lower end of each lever 40, pro- 130 jects downwardly through the slots 35, be- 135 tween the prongs 34, of the ejector plates, of the respective coin tubes, and is held pressed against the inner ends of the ejector plates to normally hold the same extended, by means of a main spring 42, engaged around the shaft 39, with one end engaged against the mounting plate 37, and with the other or lower end engaged around the rear edge of the respective lever 40. Engaged 130

on the shaft 39, adjacent one of the lugs 38, of each of the yoked brackets are second or auxiliary springs 43, one end of each of which is engaged against the mounting plate 37, while the lower end extends downwardly and is engaged in a notch for the purpose formed in the upper bent end of an upwardly projecting foot or arm 44, integrally formed or rigidly secured on the 5 rear portion of each of the ejector plates 20. Integrally formed or rigidly secured on the rear end of each of the ejector plates 19, is a foot or arm 45, which projects upwardly to engage behind the rear end of the respective 10 ejector plates 20. Formed on the rear end of each of the ejector plates 21, is an upwardly projecting foot or arm 46, the upper end of which is bent outwardly and provided with a notch to receive the lower 15 end of an actuating spring 47, which is engaged around the shaft 39, and has the upper end bearing against the mounting plate 37. Secured or formed on the rear end of each of the ejector plates 22, is an upwardly 20 projecting foot or arm 48, the upper end of which is bent outwardly and notched to receive the lower end of a spring 49, which is engaged around the shaft 39, and has the upper end bearing against the mounting 25 plate 37.

The operation is as follows:

With the parts assembled as shown and described pennies, nickels, dimes, quarters and half dollars, are manually stacked in the 30 respective coin tubes 9, 10, 11, 12 and 13. Normally the ejector plates are held projected forwardly by their respective springs so that the coin openings 29, register or are disposed below the coin tubes to 35 permit the lowermost coins to seat in said openings one above the other with the lowermost coin in each stack resting upon the base plate 16.

To cause ejection of a single penny from the tube 9, the key or button 30, designated 40 1, is pressed downwardly toward the coin holder, thereby sliding the ejector plate 19, inwardly beneath the respective ejector plates 20, into a position wherein the outer 45 end of the slot 26, is engaged against the guide pin 27, to limit the inward movement of said ejector plate 19. With the movement of the ejector plate 19, the lowermost coin in the tube 9, which is seated in the opening 29, of said ejector plate, is carried thereby into a position wherein the opening 29, registers with the opening 18, formed in the base plate 16. The coin falls by gravity through the opening 18, into the chute 4, within the 50 casing 1, and slides downwardly therein and is discharged into the receiving cup 6. Upon release of the button 30, the respective lever 40, under the stressed action of its spring 42, acts automatically to return said ejector 55 plate 19, to its normal position.

If it is desired to eject two pennies from the tube 9, the button 31, associated with said tube, is depressed, thereby forcing the ejector plate 20, inwardly together with the ejector plate 19, disposed therebelow and 60 having the foot 45, thereof projecting upwardly behind the rear end of said ejector plate 20. The simultaneous movement of both of the ejector plates 19 and 20, inwardly carries the two lowermost coins into 65 a position wherein they drop by gravity through the opening 18, into the chute 4, to be discharged into the cup 6. Release of the button 31, permits the springs 42 and 43, through the lever 40 and the foot 70 44, to automatically return the ejector plates 19 and 20, to normal position, thereby permitting the coins in the tube 9, to move downwardly through the registering openings 29. Three and four pennies may be 75 discharged from the tube 9, by depressing the respective buttons 32 and 33, thereby causing simultaneous inward movement of the ejector plates 19, 20 and 21, or 19, 20, 21 and 22, depending upon the button depressed. The inward movement of said 80 ejector plates permits the coins seated in the openings 29, thereof to fall through the opening 18, to be discharged into the cup 6. The arrangement of the various feet 44, 45 and 46, of the ejector plates 20, 19 and 21, respectively, permits the selective operation of said ejector plates to be made to afford a means whereby the ejection of any 85 desired number of coins from the coin tube 9, may be effected.

In a similar manner, one or any selective number of coins can be ejected from any of the coin tubes 10, 11, 12 and 13, by depressing the proper keys or buttons associated with said tubes, whereby coins of different denominations may be ejected as required.

The compact arrangement of the coin holder ejecting mechanisms, permits any desired selective combination of keys or buttons associated with the various coin tubes to be made by one hand of an operator with a single operation to cause the ejection of the required number of coins from the respective coin tubes to make a desired amount of change. To change a dollar the buttons 30, of the coin tubes 10, 12 and 13, together with the button 31, of coin tube 11, are simultaneously depressed by the fingers of one 100 hand of an operator, thereby causing the ejection of a nickel, a quarter, a half dollar and two dimes, into the cup 6. In like manner any desired amount of change may be made by a selective operation of the ejector 105 buttons. It will of course be understood that the coin tubes may be equipped with any desired number of ejectors, other than the number herein shown and described. It is never necessary to depress more than one 110

button of a particular coin tube at the same time to produce the ejection of a desired number of coins, and consequently any desired or selected change combination may be made by a single operation of one hand of an operator, since there will not be more than five button depressions required at a single time.

The levers 40, due to the action of the master springs 42, act to automatically return the various ejector plates, which have been depressed, to normal position, while the auxiliary springs 43, 47 and 49, associated with the respective ejector plates 20, 21 and 22, respectively, assist in the return of the ejector plates when two or more ejector plates of a coin tube are depressed at one time. The coins of the different denominations disposed in the various coin tubes, automatically feed downwardly as the lowermost coins are ejected, as soon as the ejector plates are returned to normal position after an ejecting operation. The inward and outward movements of the ejector plates is limited by the guide pins 27, engaged in the slots 26.

Where three or more ejecting plates are associated with a single coin tube, the plates may be cut away, as denoted by the reference numeral 24, to permit a selective operation of said plates by the buttons attached thereto.

We are aware that numerous details of construction may be varied through a wide range without departing from the principles of this invention, and we therefore do not purpose limiting the patent granted otherwise than necessitated by the prior art.

We claim as our invention:

40. 1. A selective change maker comprising a coin tube for holding a stack of coins of the same denomination, a plurality of superimposed apertured ejectors slidably disposed

therebelow and adapted to receive the lowermost coins in said tube seated therein, means 45 on said ejectors for selectively operating the same to cause the ejection of one or more coins from said tube by a single operation of one of said means, a shaft mounted on the back of said coin tube, a lever pivoted thereon and engaging said ejectors, a main spring mounted on said shaft for automatically returning the ejectors to normal position after the same have been operated, and auxiliary springs on said shaft and engaging a number of said ejectors to assist in returning the same to normal position.

2. In a change maker of the class described, a casing, a coin discharge chute disposed therein, a cup secured to said casing for receiving coins from said chute, a coin holder mounted to close the upper end of said casing and adapted to hold a plurality of stacks of coins each coin stack of a different denomination of coins, selectively operable mechanism projecting through said holder and associated with each of said stacks of coins and adapted to be selectively operated to simultaneously effect a discharge of one or more coins from each of a selective 70 number of said coin stacks into said coin chute, a spring controlled lever on the back of said coin holder for automatically returning said mechanisms to normal position, and auxiliary springs connected with certain of 75 said mechanisms to assist in returning the same to normal position after the operation thereof.

In testimony whereof, we have hereunto subscribed our names in the presence of two 80 subscribing witnesses.

MAX C. BRUHN.
GEORGE F. MCGILL.
